UNITED STATES PATENT OFFICE.

GÉZA NYILAS, OF HERMAND, CZECHOSLOVAKIA.

JACKET CAPABLE OF CONVERSION INTO A KNAPSACK OR TOURIST'S GROUND SHEET
OR LITTER.

Application filed December 5, 1923. Serial No. 678,755.

To all whom it may concern:

Be it known that I, GÉZA NYILAS, a citizen of the Czechoslovakia Republic, residing at Hermand, in the Czechoslovakia Republic, have invented certain new and useful Improvements in a Jacket Capable of Conversion into a Knapsack or Tourist's Ground Sheet or Litter, of which the following is a specification.

10 The object of the present invention is a jacket which is capable by means of simple hand-operated adjustments of being converted into a knapsack, tourist's ground sheet or litter which is admirably adapted 15 to the use of persons who have to be out in the open air, such as foresters, soldiers on manoeuvres, sportsmen and the like. The jacket is so constructed that out of its separate parts, such as the breast and the back, 20 the sleeves and the hood, it is possible to form the knapsack, tourist's ground sheet and the like, so that the person who carries the jacket is not obliged to burden himself with a lot of extra weight, which has a tendency 25 to grow constantly heavier.

In the accompanying drawings there is illustrated a constructional form of the object of the invention, in which:—

Figures 1, 2 and 3 show a front, side and 30 rear view respectively of the jacket; Fig. 4 the jacket converted in a knapsack; Fig. 5 the jacket converted into a tourist's ground sheet; Fig. 6 a detail of construction.

The principal parts of the jacket are the 35 breast-pieces 1, 2 which are buttoned together in front in the usual manner, the back piece 3, which is stitched to the latter, and the sleeves 10, which are attached thereto. The upper portion of the jacket terminates in a collar 4, through which a cord 23 is drawn. The shoulders of the jacket have 40 extension pieces 5, below which the sleeves 10 may be attached by means of buttons 6; the extension pieces 5 may furthermore be connected by means of the bands 8 at their 45 lower end with the buckles 9 attached to the sleeves. The sleeves 10 terminate in a folded-back cuff 11, which is provided with a series of perforations 22 and capable of 50 being fastened by means of a buckle 12, while at their upper end there is attached a hook 7 which is capable of being inserted through the extension piece 5. The back piece is continued so as to form a flap 17 55 which is folded back inside the jacket and is

secured to the back piece 3 by means of clasps 19 or buckles.

The upper portion of the back piece 3 terminates in a hood 13, which is double-walled and made of material impervious to air, and 60 can be inflated by means of a valve 16 and connected with the back piece by a band on a ring 14 and a buckle attached to the back piece.

If it is desired to convert the jacket into 65 a knapsack (Fig. 4) the clasps or buckles 19 are first undone and the flap 17 withdrawn from the inside of the jacket and made fast on the hooks 21 on the breast pieces 1, 2. The button fastenings of the sleeves 10 are 70 then detached and the armholes of the jacket are closed by connecting the extension pieces 5 by means of the band 8 with the buckles 18 situated on the side of the jacket. The sleeves 10 are folded together, the hook at 75 the upper end 17 is inserted into the ring 20 in the lower border of the jacket, the cuffs 11 at the lower end of the sleeves are extended and through the series of perforations 22 therein the cord 23 which passes 80 through the collar 4 is drawn and the ends secured. The sleeves 10 secured in this manner serve as straps and by their aid the knapsack can be carried on the shoulders.

If it is desired to use the jacket as a 85 ground sheet, the same is extended in the manner illustrated in Fig. 5, the hood is inflated through the valve 16 and the extended jacket is held in tension by means of the cords 24 attached to the pegs 25, in such a 90 manner that the wooden pieces attached to the free ends of the cords 24 are passed through the button-holes and turned transversely therein, (Fig. 6).

The mode of attaching the remaining 95 cords requires no further explanation.

If the jacket when spread out is attached, not to the pegs stuck in the ground, but to two rods, a litter (hammock) is then obtained.

I claim:

1. A jacket convertible into a knapsack, tourist's ground sheet and litter comprising a back piece and integral side and breast portions, a flap forming an extension of the back piece, detachable sleeve portions, flaps adjacent the armholes, and an inflatable hood for use as a pillow when the jacket is spread upon the ground, substantially as described.

2. A jacket convertible into a knapsack, tourist's ground sheet and litter comprising a back piece and integral side and breast portions, a flap forming an extension of the back piece, means on the back and breast portions for securing the corners of said flap when folded, detachable sleeve portions, flaps adjacent the armholes, and an inflatable hood for use as a pillow when the jacket is spread upon the ground, substantially as described.

3. A jacket convertible into a knapsack, tourist's ground sheet and litter comprising a back piece and integral side and breast

portions, a flap forming an extension of the back piece, means on the back and breast portions for securing the corners of said flap when folded, detachable sleeve portions, means for securing said sleeve portions as straps to the top and bottom of the jacket when used as a knapsack, flaps adjacent the armholes and having means for securing same in position covering said armholes, and an inflatable hood for use as a pillow when the jacket is spread upon the ground, substantially as described.

GÉZA NYILAS.
